C. ADAMS-RANDALL.
CIRCUITS FOR TELEPHONE REPEATING SYSTEMS.
APPLICATION FILED JAN. 3, 1911.

Patented Nov. 14, 1911.

UNITED STATES PATENT OFFICE.

CHARLES ADAMS-RANDALL, OF NEW YORK, N. Y., ASSIGNOR TO RANDALL TELEPHONE MANUFACTURING COMPANY, OF AUGUSTA, MAINE, A CORPORATION OF MAINE.

CIRCUITS FOR TELEPHONE REPEATING SYSTEMS.

1,008,882.

Specification of Letters Patent. Patented Nov. 14, 1911.

Application filed January 3, 1911. Serial No. 600,648.

To all whom it may concern:

Be it known that I, CHARLES ADAMS-RANDALL, a citizen of the United States, residing at New York city, in the county of New York and State of New York, have invented certain new and useful Improvements in Circuits for Telephone Repeating Systems; and I do hereby declare the following to be a full, clear, and exact description of the invention, such as will enable others skilled in the art to which it appertains to make and use the same.

This invention relates to telephone repeating systems, and has for its object to produce a system of this nature involving independent main line sending and receiving circuits adapted to repeat one into the other, and involving a relay or controller connected from one side of one of the main lines to the ground, all as will be more fully hereinafter disclosed and particularly pointed out in the claims.

Referring to the accompanying drawing forming a part of this specification in which the figure is a diagrammatic view of a system arranged in accordance with my invention—1 indicates the usual receiver hook, 2 a connection between the same and the contact lever 3, while 4 represents a push button adapted to close the circuit between said lever 3 and the contact 5.

When the parts are in the position shown in the drawing, current may flow from the main line battery 6 through the impedance 7, over the line 8, contact 9, lever 1, connection 2, lever 3, contact 5, connection 10, wire 11, and impedance 12, to the ground 13. Current may be supposed to pass from the ground 14 over the connection 15 through the coils of the relay 16, and connection 17 back to the battery 6. The passage of current through said coils of relay 16 will cause the armature 18 of said relay to be attracted, and the circuit to be closed at the contact 19. Current now flows from the local battery 20 over the connection 21 through the armature 18, contact 19, local wire 22 through the coils of the controller 23, connection 24 and over the connection 25 back to the local battery 20. The passage of current through the coils of the controller 23 causes the latter to attract its armature 26 and to close circuit at the contacts 27, 28 and 29. A person at an eastern station E now wishing to communicate with a western

station W will speak into the transmitter 30, which will cause currents from the battery 33 to traverse the primary 31 of the induction coil 32, and these voice-caused currents will cause induced currents in the secondary 33 of said coil which may be considered as leaving one end of said coil 33 over the connection 34 and passing through the connection 10, contact 5, lever 3, connection 2, lever 1, contact 9, main line wire 8, 65 and wire 35 into the condenser 36. The passage of currents into the condenser 36 will cause similar currents to flow out of said condenser along the main line sending circuit 37 through the coils of the repeater 38 over the main line sending circuit wire 39, the armature 26, the contact 28, main line wire 40, receiver 41, wire 42, and back to the other end of said coil 33. The passage of currents through the coils of the repeater 38 will cause said repeater to vary the resistance over its contacts 43 and 44, which will cause variable currents to flow from the local battery 45 over the local connection 46, through said contacts 43 and 44, 80 over the connection 47, primary coil 48, of the induction coil 49, local connection 50, contact 29 and local connection 51, back to said battery 45. The passage of varying currents similar to the original currents generated at the transmitter 30 over the primary 48 of the said coil 49 will cause similar currents to be induced in the secondary 52 of said coil 49, and these currents may be supposed to leave one end of said coil 52 over 90 the western main line receiving circuit 53, wire 54, wire 55 and into the condenser 56. The passage of currents into the condenser 56 will cause similar currents to flow out of said condenser along the western main line 95 connection 57, contact 58, lever 59, connection 60, lever 61, contact 62, connection 63, receiver 64, connection 65, contact 27, connection 66, and back to the other end of said secondary coil 52. The passage of these induced currents through the western receiver 64 similar to the voice-caused currents originally sent out from the transmitter 30 will reproduce the words at the western station which were spoken at the eastern station. 105

When it is desired to talk from the western station to the eastern station, the push pin 4 at the eastern station of course is released and the spring 71 causes the lever 3 to close circuit with the contact 72, and 110

therefore breaks the circuit at the contact 5. The breaking of the main line circuit at said contact 5, of course causes the relay 16 to be deenergized, and thereupon the spring 73 controlling the armature 18 causes the latter to make circuit at the contact 74. The making of the circuit at said contact 74 permits current to flow from the local battery 20 over the connection 21, the armature 18, said contact 74, the local wire 75, the coils of the western controller 76, local wire 77, and local connection 25 back to the said battery 20. The passage of current through the coils of said controller 76 attracts its armature 78 and causes circuit to be made at the contacts 79, 80 and 81. The operator at the western station W upon pressing in the push button 83, makes circuit at the contact 84, and upon talking into the transmitter 85 causes currents from the battery 86 to traverse the primary 87 of the induction coil 88 in the manner well known. The passage of currents through said primary 87 induces currents in the secondary 89 of said coil 88, which may be considered as leaving one end of said coil 89 over the western main line circuit 90, main line connection 54, western main line wire 92, the coils of the western repeater 93, main line wire 94, armature 78, contact 80, western main line circuit 95, connection 65, receiver 64, connection 63, contact 62, lever 61, connection 60, lever 59, contact 84, and connection 96 back to the other end of said secondary coil 89. The passage of these induced currents through the coils of the western repeater 93 varies the resistance across the contacts 98 and 99 of said repeater, which permits varying currents to flow from the local battery 100 over the local connection 101, through said contacts 98 and 99 through the connection 102, primary 103, of the coil 104, local connection 105, contact 81, local connection 106, back to said battery 100. The passage of these varying currents similar to the original current sent out from the secondary 89 through the primary 103 induces currents in the secondary 107 of said induction coil 104, which may be supposed to leave said coil at one end over the main line wire 108, main line connection 37, and into the condenser 36. Similar currents pass out of said condenser over the main line 35, main line connection 8, contact 9, lever 1, connection 2, lever 3, contact 72, and into the condenser 109. Similar currents likewise pass out of said condenser 109 over the connection 110, connection 42, receiver 41, connection 111, contact 79, connection 112 and back to the other end of said coil 107. The passage of these currents similar to the original voice-caused currents through the eastern receiver 41 of course reproduces the speech originally uttered at the western station W.

So far as now disclosed this application is somewhat similar to my co-pending application filed on the twentieth day of December, 1910, Serial No. 598,845, entitled "Telephone repeating systems connected by a single relay," but the present application involves the following difference over said co-pending application:—In the present application instead of having the relay or a controller in a complete main line circuit, it is connected from one side of the main line, and as shown, through the impedance 7, battery 6, and connections 17 and 15 to the ground 14. It is also connected from the other side of said main line through contact 9, lever 1, connection 2, lever 3, contact 5, connections 10 and 11 and impedance 12 to the ground 13. By this arrangement, of circuits, it will be seen that the secondary 33 and receiver 41 are out of the grounded circuit, and therefore the resistance of said circuit is reduced. Further, by locating the relay in the grounded circuit as disclosed so far as the effective action of said relay and the battery 6 are concerned it does not make any difference how many bridges or short circuits are connected across the metallic main line connections 8 and 40. By arranging the circuits as indicated however, detrimental effects due to bridges or short circuits between the usual main line connections 8 and 40 is entirely overcome, as will now appear. That is to say, as is well known, the calling apparatus, drops and receivers of telephone systems are frequently placed in bridges across or between connections similar to the main line wires 8 and 40, as indicated at 150 and when a relay or controller such as 16 is in a main line circuit such as disclosed in my co-pending application above, for example, the most effective use of the battery currents is prevented, as these bridges constitute short circuits, and thereby deflect more or less of the main current between terminal stations, or for example, between a terminal station and an intermediate station. In practice this loss of power is obviated by including a condenser in the bridged circuits, but these condensers themselves are objectionable for well known reasons. My arrangement of circuits, however, obviates said objections, and enables me to employ as many bridges without condensers as desired between portions of the same main line circuit as is apparent from the drawings.

It is obvious that those skilled in the art may vary the arrangement of circuits without departing from the spirit of my invention and therefore I do not wish to be limited to that shown except as may be required by the claims.

What I claim is:—

1. In a telephone system the combination of a main line sending circuit; an independent main line receiving circuit; means for

130

repeating from one of said circuits into the other; and an electro-magnetic device governing one of said circuits connected on one side to a part of one of said circuits through an impedance and a battery, and on the other side to said part through a switch and an impedance, substantially as described.

2. In a telephone system the combination of a main line sending circuit; an independent main line receiving circuit; means for repeating from one of said circuits into the other; an electro-magnetic device governing one of said circuits connected on one side to a part of one of said circuits through an impedance and a battery, and on the other side to said part through a switch and an impedance; and a bridge between said part and another portion of said main line circuit, substantially as described.

20 3. In a telephone system the combination of independent main line sending and receiving circuits; repeaters and local circuits associated with said main line circuits, and

an electro-magnetic device governing said circuits connected on one side through an impedance to a part of one of said circuits, and also connected on the other side to said part through an impedance, substantially as described.

4. In a telephone system the combination of independent main line sending and receiving circuits; repeaters and local circuits associated with said main line circuits; an electro-magnetic device governing said circuits connected on one side through an impedance to a part of one of said circuits, and also connected on the other side to said part through an impedance; and a bridge joining said part with another part of the same circuit, substantially as described.

In testimony whereof, I affix my signature, in presence of two witnesses.

CHARLES ADAMS-RANDALL.
